UNITED STATES PATENT OFFICE.

JOHN B. GILLILAND, OF BELLEVUE, PENNSYLVANIA.

ASH-REMOVER FOR GAS-PRODUCERS.

1,319,328.

Specification of Letters Patent. Patented Oct. 21, 1919.

Application filed March 11, 1919. Serial No. 281,984.

To all whom it may concern:

Be it known that I, JOHN B. GILLILAND, a citizen of the United States, residing at Bellevue, in the county of Allegheny and 5 State of Pennsylvania, have invented a new and useful Improvement in Ash - Removers for Gas-Producers, of which the following is a full, clear, and exact description, reference being had to the accompanying drawings, forming part of this specification, in which—

Figure 1 is a vertical longitudinal section through one form of gas producer and one form of ash pit, to which I have applied 15 one particular form of my improved remover.

Fig. 2 is a sectional plan view; and

Fig. 3 is an end view.

The object of my invention is to provide 20 a mechanically driven ash remover which may be continuously or intermittently driven, actuating mechanism for removing the ashes from the ash pit of a gas producer with the least amount of agitation to the 25 water seal at the lower end of the producer.

The precise nature of my invention will be best understood by reference to the accompanying drawings which will now be described, it being premised, however, that 30 various changes may be made in the details of construction and general arrangement of the parts without departing from the scope of my invention as defined in the appended claims.

35 In the drawings the reference character 2 designates the producer which may be supported in any suitable manner, and supported at the lower end of the producer is a grate 3 which may be of any desired form 40 and supported in any desired manner.

Located below the grate 3 and the lower end of the producer is an ash pit which is so situated as to form the usual water seal in the lower end of the producer and is provided 45 with downwardly and outwardly extending walls 4 which are arranged to deliver the ashes to pockets 5 on each side of the center of the structure, and which pockets are below the line of the water seal, and 50 are each provided with downwardly and outwardly inclined off-take openings 6. Pivotally mounted within each of these pockets is an ash remover, each of which comprises an end member 7 and a connecting ash removing shoe 8. This ash remover 8 is of 55 triangular form, the front end thereof being

pointed so as to readily pass under the ashes in the pocket, while the heel end thereof is blunt and arranged to raise the ashes and deliver them to the openings 6 when the device is oscillated.

Pivotaly mounted in suitable frame-work at opposite sides of the producer, are shafts 9, and connected to each shaft 9 are two crank arms 10, each of which is connected to 65 one end of a link 11, which links 11 are in turn connected to one end of an ash remover. These shafts 9 are also each provided with a gear wheel 12, each of which meshes with a pinion 13 on a shaft 14. These shafts are journaled in bearings on the frame-work and are connected to each other by means of a link belt 15 which engages suitable sprocket wheels 16, there being one sprocket wheel on each of the shafts 14.

75 17 is a beveled wheel connected to one of the shafts 14, and which is engaged by a beveled wheel 18 on a vertical shaft 19. The lower end of this vertical shaft 19 engages with a worm wheel 20 which is actuated by a worm 21 on a shaft 22. This shaft 22 has connected thereto a worm wheel 23 which is in mesh with the worm 24 on a shaft 25 driven by a motor 26. The motor 26 is connected to any suitable source of 80 energy and when the motor is driven the ash removers will be slowly oscillated in a continuous manner to remove the ashes from the pockets 5 and deliver them to the outlets 6. The gearing is of such a character that a 85 very light motor can be used as the oscillation of the ash removers is very slow so that said ash removers may be continually operated during the operation of the gas producers, or if desired they may be intermittently operated.

90 The advantages of my invention result from the provision of a reciprocating or oscillating ash remover mounted for movement in the ash pit of the gas producer, and 100 which is arranged to remove the ashes during one movement thereof, and to pass under the ashes in the pit during the reverse movement thereof, and which is also so arranged that it will deliver the ashes to an 105 off-take chute or outlet from which the ashes may be delivered by any suitable source by means of gravity.

I claim:

1. A gas producer having a water sealed 110 ash pit, an oscillating ash remover mounted in opposite ends of the pit, and arranged to

remove the ashes therefrom and deliver them to suitable outlets, a shaft at each end of the structure, gearings connecting said shafts, actuating connections between said shafts and the ash removers, a driving motor and reducing gearing between the driving motor and said shafts, substantially as described.

2. A gas producer having an ash pit comprising a pocket formed with downwardly and outwardly inclined inner wall, an outlet from said pocket, an oscillating remover in said pocket, a wedge shaped member carried by said remover for delivering the ashes to the outlet when the remover is oscillated in one direction and arranged to pass under the ashes when moving in the opposite direction, and means for oscillating said remover, substantially as described.
- 20 3. A gas producer having a water-sealed ash pit, said pit comprising pockets having downwardly and outwardly inclined inner walls, said pockets projecting at each side

of the ash pit, an oscillating ash remover in the outer part of each of said pockets, and 25 mechanical means for oscillating said ash removers to deliver the ashes to suitable outlets, substantially as described.

4. A gas producer having a water-sealed ash pit comprising pockets, said pockets 30 having downwardly and outwardly inclined inner walls, an oscillating ash remover mounted for oscillation in each of said pockets, said ash removers each having a wedge shaped member formed thereon and 35 arranged to pass under the ashes when moving in one direction and to raise the ashes to a suitable outlet when moved in the opposite direction, an actuating shaft for each ash remover, gearings connecting said shafts, 40 and means for continuously actuating said shafts, substantially as described.

In testimony whereof, I have hereunto set my hand.

JOHN B. GILLILAND.
